No. 823,295.

PATENTED JUNE 12, 1906.

E. O. SCHWEITZER.

DEVICE FOR CONTROLLING ELECTRICAL CIRCUITS.

APPLICATION FILED MAR. 26, 1904.

UNITED STATES PATENT OFFICE.

EDMUND O. SCHWEITZER, OF CHICAGO, ILLINOIS.

DEVICE FOR CONTROLLING ELECTRICAL CIRCUITS.

No. 823,295.

Specification of Letters Patent.

Patented June 12, 1906.

Application filed March 26, 1904. Serial No. 200,130.

To all whom it may concern:

Be it known that I, EDMUND O. SCHWEITZER, a citizen of the United States, residing at Chicago, in the county of Cook and State 5 of Illinois, have invented a certain new and useful Improvement in Devices for Controlling Electrical Circuits, of which the following is a full, clear, concise, and exact description, reference being had to the accompanying 10 drawings, forming a part of this specification.

My invention relates to devices for opening or otherwise controlling electrical circuits upon the passage of unduly strong or 15 overload currents.

Prominent objects of the invention are to provide a simple, practical, and effective device of this kind, to secure quick operation, to avoid harmful effects, to render unnecessary the introduction into the circuit of high 20 resistances, to permit accuracy of operation and control, to secure simplicity and cheapness of construction, and to provide a form of device particularly adapted for use in man-hole-boxes of power and lighting systems. 25

In the accompanying drawings, Figure 1 is a front elevation of a device of the class specified embodying my present invention. Figs. 2 and 3 are vertical sections of the same, 30 taken on lines 2-2 in Fig. 1, with the device in unoperated and operated conditions, respectively. Fig. 4 is a top plan view of the device, and Fig. 5 is a section taken on line 5-5 in Fig. 1.

The device shown in the drawings for carrying out my invention comprises a case 1 in the form of an inverted cup and a plug or closure 2, which is adapted to fit into the lower end of the case 1, the case and plug being conveniently screw-threaded to permit ready insertion and withdrawal of the latter. The case 1 can be of any suitable or desired cross-section, being shown with a circular cross-section. It is constructed with a convex top and a concave bottom, providing a lower wall or partition 3, having a central opening or aperture 4. The plug 2 is also conveniently of circular form and is made hollow or chambered and provided with a top wall 5, having an opening 6, which registers and corresponds with the opening 4. These two parts are desirably made of insulating material—such, for instance, as ebonite. A pair of metal plugs or rods 7 8 are in-

serted through the walls of the case 1 on opposite sides of such case, as shown in Fig. 2. The plugs 7 8 are of conducting material—such, for example, as brass or copper. The plug 2 is provided with a depending tube 9, of transparent material, such as glass, which tube 6c communicates with the interior or chamber of the plug 2. A diaphragm 10, consisting of a layer of prepared paper or similar material, is interposed between the walls 3 and 5 of the case 1 and plug 2, respectively, and closes the passage-way formed by the apertures 4 and 6. The interior of the case 1 is normally filled with mercury 11 or a similar fluid. An adjustable screw 12, Fig. 1, is inserted in the wall of the case 1 and arranged to be adjusted in and out, so as to, in effect, vary the size of the chamber of the case 1.

As a means of attaching the device and also making connection when attached in position—as, for example, in a manhole-box—a pair of metal clips 13 and 14 are secured to the case 1 by means of screws 15 15 and 16 16, respectively. One of the screws 15 desirably passes into the plug 8 and one 80 of the screws 16 into the plug 7, whereby the clips 13 and 14 make connection with the two plugs 8 and 7, respectively. The clips 13 and 14 are provided with slots 17 and 18, respectively, whereby the device can be attached by means of screws or bolts. The plug or closure 2 is desirably provided with a vent or outlet 19 and also with a pair of terminals 20 20, which are understood to be connected with some local circuit, as a relay 90 or alarm circuit.

The operation of the device is as follows: When the device is secured in position—as, for example, in a manhole-box—connection is made by the clips 13 and 14 with two terminals of the circuit, so that the current passes from said clips to the metallic plugs or contacts 7 and 8 and thence through the mercury 11. So long as the current remains normal the current passes through the mercury and the device preserves its initial condition. When, however, the current becomes abnormal to a predetermined extent or remains abnormal to a less extent for a predetermined time, the mercury 11 expands 105 and causes the breakage of the diaphragm 4, whereupon the mercury is released and falls or flows into the plug 2 and the tube 9, there-

by opening the circuit between the terminals 7 and 8 and by its presence in the tube 9 indicating that the device has operated. The presence of the mercury in the plug 2 5 causes connection to be made between the contacts 20 20 thereof, whereby the local relay or alarm circuit is closed to ring an alarm or otherwise call attention to the fact that the device has operated. The vent 19 permits the access of air to the interior of the device to facilitate the descent of the mercury.

From the foregoing it will be seen that the device is simple and practical and effective, that it can be made to operate with great accuracy, and that the operation occurs as a result of expansion and not as a result of fusion, as is common in circuit-breaking devices, wherefore operation occurs with but a slight increase in heat. It will also be seen that no 20 high resistance is introduced into the circuit by the device, the mercury having a high conductivity and being present in such large quantity as to offer a negligible resistance. It will also be seen that the time limit of operation of the device can be easily regulated by adjusting the screw 12 so as to, in effect, vary the size of the chamber in the case 1, and thereby subject the mercury to a greater or less pressure.

30 The device can be designed and constructed for different conditions—that is, different sizes of current, different time limits of operation, &c.—by varying the size and shape of the mercury-containing case, it being observed that operation naturally depends on the size of the conductor, its conductivity, and its coefficient of expansion.

It will be understood that changes and modifications can be made in the device 40 without departing from the spirit of my invention.

What I claim is—

1. A cut-out for electrical circuits, comprising a mobile conductor, and a closed case 45 confining said conductor and having a fracturable retainer adapted to be fractured on the expansion of said conductor by the passage of an unduly strong current through it, said cut-out having provisions for including 50 said conductor normally in circuit.

2. A thermal cut-out, comprising a closed case containing a liquid conductor, and having a fracturable retainer normally holding said conductor confined in said case, but 55 adapted to be fractured on the expansion of said conductor by the passage of an unduly strong current, said cut-out having provisions for including said conductor normally in the circuit.

60 3. A cut-out, comprising a case made of insulating material, and provided with conducting contacts extending through its walls, a body of mercury confined in said case, said case having an aperture, and a fracturable 65 retainer normally closing said aperture and

adapted to be fractured by the expansion of the mercury by the passage of an unduly strong current through it.

4. A cut-out device comprising a case having a structurally separate fracturable retaining-section, and having provisions for including a conductor within the case in circuit. 70

5. A cut-out device, comprising a case made of insulating material and provided with conducting contacts extending through 75 its walls, said case having an aperture, and a fracturable retainer normally closing said aperture.

6. In a device of the class specified, the combination with a case or receptacle, of a 80 body or mass of conducting liquid confined in said case or receptacle and included in the circuit, and a retainer for holding said liquid in suspense, said retainer being adapted to be actuated so as to permit the liquid to fall by 85 the expansion of the same on the passage of an unduly strong current, substantially as described.

7. In a device of the class specified, the combination with a case or receptacle, of a 90 body or mass of conducting liquid confined in said case or receptacle and included in the circuit, a retainer for holding said liquid in suspense, said retainer being adapted to be broken or fractured to permit the liquid to 95 fall by the expansion of the liquid on being heated by the passage of an unduly strong current, substantially as described.

8. In a device of the class specified, the combination with a case or receptacle, of a 100 liquid contained therein, a retainer for holding the liquid in said case or receptacle, whereby on the expansion of the liquid by an unduly strong current, the liquid will be released, and a second receptacle for receiving 105 the liquid when released, substantially as described.

9. In a device of the class specified, the combination with a case or receptacle, of a 110 quantity or mass of conducting liquid confined in said case, a diaphragm for holding said liquid in suspense, whereby when the liquid is expanded by an unduly strong current, the diaphragm will be broken or ruptured, and the liquid permitted to fall, and a 115 second receptacle for receiving the liquid when so released, substantially as described.

10. In a device of the class specified, the combination of a case, a body or mass of conducting liquid contained therein, terminals 120 in said case, adapted to make contact with said liquid therein, the bottom of the case being provided with an aperture, a diaphragm closing said aperture, and a chambered plug adapted to fit into the bottom of said case 125 and having its upper wall provided with an aperture below said diaphragm, substantially as described.

11. In a device of the class specified, the combination of a case, a liquid contained 130

- therein, a diaphragm holding said liquid normally in suspense, and a receptacle for the liquid when released, said receptacle being formed of transparent material, substantially 5 as described.
12. A device of the class specified, comprising a case provided with a pair of terminals and having its bottom provided with an aperture, a body or mass of liquid contained 10 in said case, a diaphragm below said aperture, a chambered plug fitted into the bottom of the case and having an aperture below said diaphragm, and a transparent tube attached to said plug, substantially as described.
13. In a device of the class specified, the combination of a case, a conducting liquid contained in the case, the latter being provided with terminals, a threaded device passing through the wall of the case and made 15 adjustable to permit variation of the size of the chamber formed by the case, a diaphragm holding the contents of the case normally therein, and a receptacle for receiving the contents of the case upon their release, 20 substantially as described.
14. In a device of the class specified, the combination with a case or receptacle provided with terminals, of a liquid conductor confined therein, means whereby the conductor can be 25 released on the passage of an unduly strong current, and a plug or closure associated with the case or receptacle for receiving the liquid when released, said plug or closure being provided with a pair of terminals between which 30 connection is made by the liquid when in said plug or closure, substantially as described.
15. In a device of the class specified, the combination with a case or receptacle provided with terminals, of a liquid conductor 35 confined therein, means whereby the conductor can be released on the passage of an unduly strong current, and a plug or closure associated with the case or receptacle for receiving the liquid when released, said plug or closure being provided with a vent for communicating with the outside air, substantially as described.
16. In a device of the class specified, the combination of a conductor included in the 40 circuit, means for inclosing or confining said conductor, said inclosing means being provided with an independent relatively fragile portion whereby when the conductor is expanded by the passage through it of an un- 45
- duly strong current, it ruptures said fragile portion, substantially as described.
17. In a device of the class specified, the combination with a mobile conductor included in the circuit, of a case confining said conductor, said casing having an independent 50 relatively fragile portion adapted to be broken or ruptured on the expansion of the conductor by the passage of an unduly strong current through it, and said conductor being arranged to be removed from circuit on the 55 breakage of said relatively fragile part so as to open the circuit, substantially as described.
18. In a device of the class specified, the combination with a conductor included in circuit, means for inclosing said conductor, a 60 retainer for holding said conductor in said inclosing means, said retainer being adapted to be removed on the expansion of the conductor by the passage through it of an unduly strong current, substantially as described. 65
19. In a device of the class specified, a case for holding a conductor said case having an independent relatively weak portion, and means for including a conductor within the case, in circuit, substantially as described. 70
20. In a device of the class specified, a containing-case provided with terminals adapted to make connection with a conductor within the case, and a fracturable retainer for normally holding the contents of the case 75 therein, substantially as described. 80
21. In a device of the class specified, a case provided with terminals extending from the interior to the exterior of the walls of the case, said case also having an opening, and a fracturable device for closing said opening, substantially as described. 85
22. In a device of the class specified, a case provided with terminals extending from the interior to the exterior of the walls of the case, 90 said case also having an opening, a fracturable device for closing said opening, and a second case adapted to be fitted to the first-mentioned case and having an opening registering with the opening in said first-mentioned 95 case and normally closed by said fracturable device, substantially as described.
- In witness whereof I hereunto subscribe my name this 23d day of March, A. D. 1904.
